UNITED STATES PATENT OFFICE.

HENRY R. TOWNE, OF STAMFORD, CONNECTICUT, ASSIGNOR TO THE YALE & TOWNE MANUFACTURING COMPANY, OF SAME PLACE.

DESIGN FOR A PATTERN FOR WRAPPING-PAPER.

SPECIFICATION forming part of Design No. 23,409, dated July 3, 1894.

Application filed September 7, 1893. Serial No. 485,022. Term of patent 14 years.

To all whom it may concern:

Be it known that I, HENRY R. TOWNE, a citizen of the United States, residing at Stamford, in the county of Fairfield and State of Connecticut, have invented and produced a new and original Design for a Pattern for Wrapping-Paper, of which the following is a specification.

My invention is a pattern for wrapping paper, which is more particularly intended to be used for wrapping or covering boxes or other receptacles, but is likewise useful in other connections where an ornamental effect is desired.

My design is illustrated in the accompanying drawing, and consists of a number of tangentially arranged circles, 1, 2, some of which (those marked 2) are ornamented by trefoil figures 3, which give them an appearance which contrasts with the plain circles. These contrasting circles are grouped substantially as shown so as to form figures 4, approxi-

mately diamond shaped. These diamond shaped figures are symmetrically disposed over the surface in such a manner as to leave 25 between them separating lines 7 made up of the plain circles 1. These separating lines run parallel to the adjacent sides of the diamond shaped groups of ornamented circles 2, and therefore cross each other and form around 30 the ornamented groups, diamond shaped borders made up of plain circles, 1.

The trefoil figures 3 provide panels for suitable lettering or words.

Having thus described my invention, the 35 following is what I claim as new therein and desire to secure by Letters Patent:

The design for a pattern for wrapping paper; substantially as herein shown and described.

HENRY R. TOWNE.
